UNITED STATES PATENT OFFICE.

LOUIS LAMBIN, OF CHICAGO, ILLINOIS.

CAN-ENDING MACHINE.

SPECIFICATION forming part of Letters Patent No. 726,799, dated April 28, 1903.

Application filed June 7, 1902. Serial No. 110,697. (No model.)

To all whom it may concern:

Be it known that I, LOUIS LAMBIN, a citizen of the United States, residing at Chicago, in the county of Cook and State of Illinois, have 5 invented certain new and useful Improvements in Can-Ending Machines, of which the following is a specification.

This invention relates to machines for pressing the formed ends of a can onto the body 10 thereof preparatory for soldering. Its object is to provide a simple machine for the purpose indicated that will be efficient in operation and of an exceedingly large capacity; and it consists in the various features of construction and details that will be described 15 hereinafter.

In the drawings, Figure 1 is a side elevation of a machine embodying this invention. Fig. 2 is a front elevation of the same, showing one section after the ends are pressed on and with parts omitted to prevent confusion. Fig. 3 is an enlarged view of a portion of the disk on the left of Fig. 2, showing the slideable sections. Fig. 4 is a section on line 4-4 25 of Fig. 3. Fig. 5 is a detail of one of the grippers. Fig. 6 is a detail of one of the saddles. Fig. 7 is a sectional view showing the can parts ready to be pressed together. Fig. 8 is a similar view after the disk-section has 30 been forced in and the ends pressed on. Fig. 9 is a detail showing means for ending cans where the head is provided with a tang for opening. Fig. 10 is a sectional plan view of the same, taken on the line 10-10 of Fig. 9. Fig. 11 is a detail showing the recesses c^{12} . Fig. 12 is a sectional view taken through a 35 portion of one of the disks, showing the recess 12 and the gripper g therein and the saddle e' .

40 A represents a frame of suitable material and outline with a base a and sides a' , in which are bearings a^2 for a revolute shaft B. This shaft may be driven in any desired manner, as by a belt around the pulley b. Rig- 45 fidly mounted on this shaft is a disk C, which for convenience will be called the "right-hand" disk, and an enlarged hexagonal hub c, which carries the left-hand sectional disk C', composed of the sections c' . Ways c^2 are 50 cut in the hub c for the bases c^3 of the sections c' . The object of sliding these sections is to press the ends upon the body after they

have been clamped in proper relative positions, and the movement is accomplished by arms c^4 , secured to the bases c^3 by bolts c^5 in 55 slotted holes c^6 . These arms are adjusted by nuts c^7 on studs c^8 , secured to the sections c' and passing through lugs c^{10} on the arms c^4 . At the ends of the arms c^4 are cam-rollers c^{11} , which are adapted to engage with cam- 60 plates d d' on a stationary cam-drum D, secured to the frame A.

The can-bodies e are fed to the machine through a chute E (shown in Fig. 1) and are caught by saddles e' , which are rigidly secured to the inner faces of the disks C and C' and form a part of the can-gripping mechanism. Immediately forward of the chute for the bodies are a pair of chutes F for the ends f . These are also caught in the saddles e' , which 65 are grooved at e^2 , next to the disks, to receive the ends and hold them in proper position for engagement with the body. After the bodies and ends have been caught by the saddles they are next engaged by grippers g , which 70 are grooved to receive the ends and coact with the saddles to securely hold the bodies and ends in proper position for ending. These grippers are semicircular in outline and normally rest in similar-shaped recesses c^{12} , cut 75 in the disks C and C'. They are provided with elongated bearings g' , which slide and turn upon short rods h , which are supported at one end by lugs e^3 on the saddles e' and at the opposite end by brackets h' on the disks. 80 Springs h^2 on the rods h tend to hold the grippers in their normal position. To cause the grippers to engage the can parts, they must first be pressed in against the action of the springs until free of the disks and then turned 85 90 until they press the can. The first movement is accomplished by means of cams g^2 on the bearings g' , which engage the cam-rollers i on the brackets a^3 from the frame A as the disks rotate. Just as the cam forces the gripper in till it is free to turn a pin g^3 on the gripper 95 engages a finger i^2 , projecting from the frame and swings the gripper down till it engages the can. The finger i^2 may be a spring or otherwise made yielding, if desired. In order to hold the gripper in positive engagement with the cans, spring-pressed catches j 100 are arranged on the disks to lock the pins g^3 .

The operation of ending the can may now

be readily understood. The disks being rotated, as shown by the arrow in Fig. 1, the can-body is first caught by the saddles and lies centrally of the disks, so that there is room at either end for the ends to drop into the grooves in the saddles. The cam next forces the grippers in, and the fingers on the frame engaging the pins on the grippers swing them into engagement and the catches hold them. The body and ends being in their proper relative positions to be pressed together, the roller on the arm extending from the base of the section engages the cam-plate and forces the section in toward the relatively stationary disk and presses the can parts together. It is customary to form one of the can ends with a central aperture, and to allow the air to escape from the can while the ends are being pressed on there are holes ¹³ through the disk centrally disposed with reference to the can. As shown in this form of construction, each section is provided with means for ending two cans. The can being ended, the catches *j* are released by striking the tripper *j'* from the frame. The grippers will then swing out by their own weight and centrifugal force until they are opposite the openings in the disks, when the springs will draw them into their normal position. The grippers having released the cans, the section *c'* will be drawn back by the roller *c''* engaging with a cam on the cam-drum D and allows the cans to be discharged into any convenient chute, such as K. (Shown in Fig. 1.)

In frequent instances it is desired to form cans with tangs for opening them after they are sealed. For this purpose I have provided the device shown in Figs. 9 and 10. The chute F is provided with a slot *f'* to register with the tangs *f''* on the ends *f*. When the end is discharged from the bottom of the chute, a spring-finger *f''* prevents the tang from turning down, and as the saddle *e'* carries the end forward a second spring *f'* engages the tang *f''* and turns the end in the saddle until the tang registers with a recess *e* in the saddle *e'*. The gripper then engages the can, and the further operation is as above described.

It will be observed that by changing the shape of the saddles and grippers any form of can may be ended, and various other changes in details of construction may readily be made, which will come within the scope of this invention, which I do not wish to limit to the exact form shown; but

What I claim, and desire to secure by Letters Patent, is—

1. In a can-ending machine, the combination of a frame, a shaft mounted in said frame, a disk mounted on said shaft, a hub mounted on said shaft adjacent to said disk and carrying a sectional disk, can body and end gripping mechanism carried by said disks and means for operating the disk-sections to press the can ends upon the bodies.
2. In a can-ending machine, the combination of a frame, a shaft mounted in said frame,

a disk on said shaft, a hub adjacent to said disk, slideable disk-sections carried by said hub, saddles on said disk and disk-sections for receiving can bodies and ends, grippers adapted to coact with said saddles to hold said bodies and ends, and means for sliding said disk-sections to press the bodies and ends together.

3. In an ending-machine, the combination of a frame, a revolute shaft mounted in said frame, a disk rigidly mounted on said shaft, a hub adjacent to said disk, slideable sections mounted on said hub, saddles on said disk and sections, grippers normally in alinement with said disks and sections, means for projecting said grippers into alinement with said saddles, means for turning said grippers to coact with said saddles and means for reciprocating said slideable sections.

4. The combination of a frame, a shaft, disks on said shaft, saddles on said disks, grippers normally reposing in apertures in said disks, bearings for said grippers on rods secured to said disks, springs tending to hold said grippers in normal position, cams on said bearings for forcing said grippers into alinement with said saddles, pins on said grippers to turn them on said rods to coact with said saddles, and catches on said disks to engage said pins.

5. In combination, a frame, a revolute shaft mounted in said frame, disks on said shaft, saddles on said disks, grippers normally reposing in apertures in said disks, bearings for said grippers on rods having their inner ends supported by said saddles and their outer ends supported by brackets on said disks, springs tending to hold said grippers in normal position, cams on said bearings, cam-rollers secured to said frame adapted to engage said cams, pins on said grippers, fingers on said frame adapted to engage said pins and turn said grippers, catches on said disks to engage said pins, and trippers on said frame for releasing said catches.

6. In combination, a frame, a revolute shaft in said frame, a disk rigidly mounted on said shaft, a hub adjacent to said disk, disk-sections slidably mounted in said hub, arms secured to said sections provided with cam-rollers, and cams on a cam-drum secured to said frame adapted to engage with said rollers to reciprocate said sections.

7. In an ending-machine, the combination of a frame, a shaft in said frame, a disk on said shaft, a hub on said shaft, disk-sections slidably mounted on said hub, saddles on said disk and sections adapted to receive a can-body and grooved to receive can ends, chutes for delivering said bodies and ends to said saddles, grooved grippers normally clear of the space between said disk and sections adapted to be projected into the path of said bodies and ends and coact with said saddles to hold said bodies and ends, means for reciprocating said sections to press said can parts together, means for releasing said grippers.

pers and returning them to their normal positions and a discharge-chute for the cans.

8. In a can-ending machine, the combination of a frame, a revoluble shaft mounted in said frame, a disk rigidly secured to said shaft, a hub on said shaft, ways cut in said hub, slidable disk-sections with bases engaging said ways, adjustable arms on said bases, cam-rollers on said arms, cams supported from said frame adapted to engage said rollers, saddles on said disks and sections, feed-chutes adapted to deliver bodies and ends to said saddles, grippers provided with bearings to engage rods held by lugs e^3 on said saddles and brackets h' on said disks, apertures in said disks for said grippers, springs tending to hold said grippers in said apertures, cams g^2 on said bearings, cam-rollers on brackets from the frame adapted to engage said cams, pins g^3 on said grippers, fingers on said frame to en-

gage said pins, catches on said disks to engage said pins, trippers on said frame to release said catches, and a discharge-chute.

9. A can-gripping device comprising a disk or portion thereof, a saddle or jaw on said disk, a gripper normally reposing in an aperture in said disk adjacent to said saddle or jaw, means for moving said grippers to clear said disk, and means for causing it to approach said saddle to grip a can. 25

10. In combination, a chute for feeding can ends provided with a slot for tangs on said ends, springs fingers for engaging said tangs, apertures in the end gripping devices for said tangs and means for forcing the ends upon the can-body. 30 35
